UNITED STATES PATENT OFFICE.

EMERICH SABINA AND LESTER I. COPE, OF SHARPSBURG, PENNSYLVANIA.

RENEWABLE CARTRIDGE-FUSE.

1,256,043.

Specification of Letters Patent. Patented Feb. 12, 1918.

Application filed October 19, 1915. Serial No. 56,704.

To all whom it may concern:

Be it known that we, EMERICH SABINA and LESTER I. COPE, citizens of the United States, residing at Sharpsburg, in the county 5 of Allegheny and State of Pennsylvania, have invented certain new and useful Improvements in Renewable Cartridge-Fuses, of which the following is a specification.

Our invention relates to electrical fuses 10 and more particularly to a renewable cartridge fuse.

The primary object of our invention resides in the provision of a cartridge fuse or shell having novel means associated therewith for removably applying and clamping a fuse within the cartridge without the use of any tools thereby providing a device of the above character which may be readily and quickly placed in an operative position.

Another object of our invention resides in the provision of novel means associated with the ends of the cartridge for protecting the ends of the cartridge and for guiding the clamping means and causing them to contract to firmly, yet removably clamp a fuse in position.

Another object of our invention resides in the provision of a novel means for mounting the blades on the respective ends of the 30 fuses.

A further object of our invention resides in the provision of a device of the character described that is simple in construction, efficient in operation and one that can be manufactured and placed on the market at a minimum cost.

Other objects as well as the nature, characteristic features and scope of our invention will be more readily understood from 40 the following description taken in connection with the accompanying drawings and pointed out in the claims forming a part of this specification.

In the drawings:—

45 Figure 1 is a longitudinal sectional view of our invention illustrating to advantage the novel means for removably clamping the fuse and blades in position, the blades being shown in side elevation;

50 Fig. 2 is a longitudinal sectional view of our invention illustrating to advantage the construction and arrangement of the clamping means and the blades, the latter being shown in plan;

55 Fig. 3 is an end elevational view of the enlarged end of the clamping means;

Fig. 4 is a front elevational view of the blade holder; and

Fig. 5 is an end elevational view of the cartridge.

Referring more particularly to the drawings in which similar reference numerals designate like or corresponding parts throughout the different views, we provide a cartridge 1 preferably a fiber tube having external screw threads 2 adjacent the respective ends thereof while the respective outer edges are provided with oppositely disposed transverse grooves 3 for a purpose to be hereinafter referred to.

In order to firmly, yet removably hold a fuse 4 in the cartridge, we have provided our improved clamping means, in this instance including two complementary semi-cylindrical and tapering gripping wedges 5 75 having longitudinal grooves 6 on their flat surfaces which, when the two gripping wedges are placed together so that they form a frusto-conical clamp, provide an elongated opening for receiving the respective ends of 80 the fuse 4. Frusto-conical guides 7 having flanges 8 on their enlarged ends are arranged upon the respective edges of the cartridge so that they project within the cartridge while the flanges are depressed at diametrically opposite points to provide ribs 9 85 which engage the grooves 3 to prevent rotation of the guides. These guides serve the dual purpose of guiding the frusto-conical clamps into position and for protecting the 90 fiber cartridge. It will now be apparent that after the fuse has been arranged within the cartridge and after the guides have been arranged in position, the respective ends of the fuse are arranged in the openings provided in the gripping wedges whereby the latter are forced within the guides and frictionally retained therein.

For the purpose of removably holding the clamping means in position and preventing 100 the accidental displacement thereof, also mounting the knife blade contacts for the fuse, we have provided our improved cylindrical internally screw-threaded metallic caps 10, each of which has centrally disposed 105 tapering openings 11 therein. Preparatory to engaging the screw-threaded caps on the screw threads 2 of the cartridge, we have associated the reduced ends 12 of rectangular and relative flat knife blade contacts 13 110 with the openings 11. Pins 14 are formed integral with and extending longitudinally

of the reduced ends of the blades and are arranged through central apertures in the blade supporting plates 15, the pins being retained on the plates by flattening them to provide heads 16 which are preferably arranged within the opening provided by the grooves 6 when the caps are secured in position. To prevent rotation of the plates 15 and the clamping means, we have formed lugs 17 at uniformly spaced intervals on the plate, the latter engaging sockets 18 provided in the enlarged ends of the gripping wedges 5. It will now be understood that when the blades and blade holding plate have been associated with the caps, when the caps are being arranged upon the ends of the cartridge, the lugs will engage the sockets and prevent accidental rotation of the blades.

The operation of our invention is as follows:

When the fuse 4 burns out, by unscrewing the caps 10, the clamping means can now be removed from about the ends of the old fuse to finally permit of the removal of the old fuse. A new fuse can now be inserted, clamped and maintained in position by the metallic clamping means and the latter maintained in position through the medium of the caps.

Although we have shown and described the preferred embodiment of our invention, we desire to be understood that we are not to be limited to the exact details shown; however, we desire that great stress be laid upon the peculiar arrangement of the clamping means, the guides therefor with which co-operate the blade holding plates and caps for providing an efficient renewable cartridge fuse.

From the above description taken in connection with the accompanying drawings, it can easily be seen that we have provided a device that is simple in construction, containing but a few simple parts that can be cheaply manufactured and assembled and when assembled can be placed upon the market and sold at a minimum cost.

It will be understood that the above description and accompanying drawings comprehend only the preferred embodiment of our invention and that various minor changes in detail of construction, proportion and arrangement of the parts may be made within the scope of the appended claims and without sacrificing any of the advantages of our invention.

Having thus fully described our invention, what we claim as new and desire to secure by Letters Patent, is:—

1. A cartridge fuse holder comprising a tubular member threaded at each end and adapted to contain a fuse, a clamping member closing each end of the tubular member and consisting of complementary sections having grooves therein to form a bore, when the

sections are together, in which the end of the fuse engages, the outer faces of the clamping member having depressions therein, a plate for each end of the fuse and adapted for engagement with the outer ends of the clamping members, said plate having projections engageable in the depressions in said clamping member, whereby the plate is held against rotation relative to the clamping members, a knife blade contact projecting from each of said plates, a ferrule for each end of the cartridge and adapted for engagement thereon, said ferrule having a flange thereon adapted to retain the plate and clamping members in position and to move the sections of the clamping member into clamping engagement with the fuse as the ferrule is threaded on the cartridge.

2. A cartridge fuse holder comprising a tubular member having notches formed in the ends thereof, frusto-conical guides extended in the ends of the tubular member and having projections for engagement in said notches for holding the guides against rotation, recessed wedge members for association with each of the guide members and having grooves therein to form a bore in which the ends of the fuse engage, a plate for each end of the cartridge and adapted for engagement with the outer ends of said wedge members and having projections thereon for engagement in the recesses in said wedge members whereby the blade is held against rotation relative to the wedge members, a knife blade contact extending from said plate, and a ferrule for each end of the cartridge to maintain said plate in position and for moving said wedge members into tight clamping engagement with the ends of the fuse as the ferrule is moved in position on the cartridge.

3. A cartridge fuse holder comprising a tubular member, a guide insertible in each end of the tubular member and having a tapering passage therein, a tapered fuse clamp insertible in the tapered passage of each guide, the tapered portions of the guides being adapted to lie spaced from the tubular member, means for forcing and maintaining the clamps in position within the guides, and a flange projecting from each guide and adapted to engage the end of the tubular member and to transmit a longitudinal pressure on the ends of the latter, when said clamping members are forced into clamping position.

4. A cartridge fuse holder comprising a tubular member composed of fiber material, a metallic truncated conical shell insertible in each end of the tubular member to form guides and adapted to have the tapered portions thereof lie spaced from the tubular member, a tapered fuse clamp insertible in each guide and composed of a plurality of complementary sections between which an end of the fuse is gripped, a cap for each end of

the tubular member to be threaded thereon and to force and hold the clamp in position in the guide, a flange projecting from each guide for engagement with the edge of the 5 tubular member to exert longitudinal pressure on the end of the latter when the clamping members are forced into clamping position in the guides.

5. A cartridge fuse holder comprising a 10 tubular member for containing the fuse, a clamping member associated with each end of the tubular member to grip an end of the fuse, a plate adapted to lie on the outer ends of each of the clamping members and carrying a knife blade contact, a cap for each end of the tubular member adapted to be removably retained thereon for holding the plate 15 in position and for moving the clamping members into clamping position, the clamping members having sockets therein, and spaced projections on the plates adapted to 20 engage with said sockets to prevent rotation of the plates as the caps are placed in posi-

tion, so that the knife blades will be retained in adjusted angular alinement with each 25 other.

6. A renewable cartridge fuse comprising a tube having threaded ends, a slotted cap to coöperate with each end of said tube, guides having flanges adapted to engage with the 30 ends of the tube, clamping members insertible in said guides, which serve to position said member out of contact with the tube, means interposed between a lateral face of each of said members and a cap to prevent 35 rotation of said members when the caps are screwed on, and a fuse adapted to be removably held in said tube by the clamping members.

In testimony whereof we affix our signatures in presence of two witnesses.
